(57) **CLAIM**

I claim the ornamental design for an outsole for a shoe, as shown and described.

DESCRIPTION

FIG. 1 is a bottom view of an outsole for a shoe showing my new design;

FIG. 2 is a right side view of the outsole for a shoe in accordance with the new design shown in FIG. 1;

FIG. 3 is a left side view of the outsole for a sole in accordance with the new design shown in FIGS. 1-2;

FIG. 4 is a front view of the outsole for a shoe in accordance with the new design shown in FIGS. 1-3;

FIG. 5 is a cross sectional view of the outsole for a shoe in accordance with the new design shown in FIGS. 1-4; and, FIG. 6 is an enlarged perspective view of the area referenced as "6" in FIG. 1.

The broken lines showing a shoe upper in FIGS. 1-4 represent the portions of the design that form no part of the claim. The broken wavy line immediately adjacent to the claimed surface in FIGS. 1-3, represents the boundary of the design with the broken line itself forming no part of the claim.
